assignors to

Daniel E. Paris, aforesaid.

Letters Patent No. 1872-Dated Dec. 1st 1868.

Design, for Stove Plates.

The schedule referred to in these Letters Patent and making part of the same.

To all whom it may concern:

Be it known that we, Daniel E. Paris and Francis E. Ritchie, each of the City of Troy, in the County of Rensselaer and State of New York, have jointly invented or produced a new and original ornamental Design for Stove Plates; and we do hereby declare that the following is a full and exact description thereof, reference being had to the annexed photographic drawing of a stove plate bearing our said ornamental design.

This new ornamental design for stove plates consists of the arrangement, upon a panel, J.J. of a peculiar compound ornament, consisting of a middle piece K, two radial stems, L.L, with side leaves, m m, n n, and two other radial leaf-stems, m m, all shaped and arranged together so as to present the appearance shown by the annexed photographic drawing.

What we claim as new and of our joint invention or production, and desire to secure by Letters Patent, is, the above described ornamental design for stove plates.
